UNITED STATES PATENT OFFICE.

ARTHUR C. JEWETT, OF NEW HAVEN, CONNECTICUT, ASSIGNOR TO WINCHESTER REPEATING ARMS CO., OF NEW HAVEN, CONNECTICUT, A CORPORATION.

SHOT-SHELL.

1,305,115.

Specification of Letters Patent. Patented May 27, 1919.

Application filed November 29, 1918. Serial No. 264,489.

To all whom it may concern:

Be it known that I, ARTHUR C. JEWETT, a citizen of the United States, residing at New Haven, in the county of New Haven 5 and State of Connecticut, have invented a new and useful Improvement in Shot-Shells; and I do hereby declare the following, when taken in connection with the accompanying drawings and the characters 10 of reference marked thereon, to be a full, clear, and exact description of the same, and which said drawings constitute part of this application, and represents a sectional view in longitudinal central section of one 15 form which my improved shell may assume.

My invention relates to an improvement in shot shells designed with particular reference to being used in trap-shooting but not limited to such use, the object being to 20 mark, for the guidance of the shooter, the path of the charge of shot.

With these ends in view, my invention consists in a shot shell having one or more ignitable flight-marking pellets embedded 25 in its charge of shot and adapted to be ignited when the shell is exploded by the concussion of the shot-charge against them and to accompany the charge of shot to mark the path thereof and to render the same 30 visible to the eye of the shooter.

In carrying out my invention as herein shown, I embed three ignitable flight-marking pellets 2 in the charge of shot 3 which is interposed between the overshot card- 35 board wad 4, and the foremost driving-wad

5 of the three felt driving-wads 5, 6 and 7 which are in front of the cardboard wad 8; otherwise the shell is of standard construction. When the shell is exploded, the pellets are ignited and accompany the charge 40 of shot during its travel the path of which they mark so as to render the same visible to the eye of the shooter. As for the pellets 2 they must have sufficient weight to accompany the charge of shot the path of which 45 they mark. Their element of ignitable material may be of any suitable composition, such as magnesium and barium peroxid. It will be understood, of course, that when 50 the contents of the shell are discharged all of the wads shortly fall to the ground.

I claim:—

In a flight-marking shot shell, the combination with the paper tube, powder-charge, wads and shot-charge thereof, of one or 55 more ignitable flight-marking pellets embedded in the shot-charge, adapted to be ignited by the concussion of the same when the shell is exploded, and having sufficient carry to follow the same so as to render the 60 flight of the same visible to the eye of the shooter.

In testimony whereof, I have signed this specification in the presence of two subscribing witnesses.

ARTHUR C. JEWETT.
